FUEL SYSTEM FOR INTERNAL COMBUSTION ENGINES

Frederick J. Holmes, Detroit, Mich., assignor, by
mesne assignments, to Nuway Engineering
Corporation, Toledo, Ohio, a corporation of
Ohio

Application December 11, 1933, Serial No. 791,992

5 Claims. (Cl. 123—127)

This invention relates to fuel systems for internal combustion engines, and has particular reference to means to adapt internal combustion engines of the type which are primarily designed to burn more or less highly refined fuels, such as gasoline, for operation by considerably heavier fuels such as commercial fuel oil.

The general object of the invention is to provide simple, reliable and efficient means whereby ordinary so-called gasoline engines, such as present day automobile, truck, boat and similar engines, may be made to operate economically and with increased power employing as fuel commercial fuel oil.

15 Included in the fuel system of the ordinary present day gasoline engine is a carburetor for atomizing the gasoline prior to its introduction into the intake manifold of the engine. In this connection a special object of the present invention is to provide a system whereby commercial fuel oil may be used as fuel for ordinary gasoline engines and whereby the carburetors ordinarily employed in conjunction with such engines may be utilized, without change, for atomizing the fuel oil.

20 In order that an ordinary carburetor employed in conjunction with an ordinary gasoline engine may be utilized for the atomization of commercial fuel oil, it is necessary that the fuel oil be heated prior to its introduction into the carburetor. Accordingly, another special object of the present invention is to provide novel and highly efficient means for utilizing the heat of the engine to heat the fuel oil during its flow to the carburetor.

25 Since, according to the present invention it is necessary to heat the fuel oil prior to its atomization in an ordinary carburetor, and since, after more or less prolonged periods of idleness of the engine the latter may become cold or insufficiently warm properly to heat the fuel oil, the invention contemplates an arrangement for using gasoline or similar light fuel for starting the engine and for using heavier oil as fuel after the engine has been started and has become sufficiently hot properly to heat the fuel oil. The gasoline and fuel oil supply pipes are controlled by a single valve which is operable to selectively deny communication between either of said pipes and the carburetor and to simultaneously place the other pipe in communication with the carburetor, and a remote control handle or equivalent valve actuator is provided whereby the valve may readily be actuated by the operator of the engine. When the engine is operating on fuel oil it is desirable that the air admitted to the carbure-

30 tor for admixture with the atomized oil shall be heated. Accordingly, the invention includes novel means for supplying heated air to the carburetor. When, however, the engine is to be started by using gasoline as fuel it is desirable that there shall be an unimpeded flow of fresh air to the carburetor. Accordingly, another special object of the invention is to provide means whereby, upon actuation of the fuel control valve to place the gasoline supply pipe in communication with the carburetor, an air supply control element is actuated to permit a free flow of fresh air to the carburetor, and whereby, upon actuation of said fuel control valve to place the fuel oil supply pipe in communication with the carburetor, said air supply control element is actuated to assure a flow of heated air to the carburetor.

35 With the foregoing and various other objects in view, which will become more fully apparent as the nature of the invention is better understood, the same consists in the novel combination and arrangement of features as will be hereinafter more fully described, illustrated in the accompanying drawing and defined in the appended claims.

40 In the drawing, wherein is illustrated one practical embodiment of the invention:

Figure 1 is a side elevation of an ordinary gasoline engine illustrating a fuel system in accordance with the invention applied thereto; and

Figure 2 is a detail view of the carburetor.

45 Referring to the drawing in detail, A designates, generally, an internal combustion engine which is designed primarily for the use of gasoline as fuel and which includes, as usual, an intake manifold 10, an exhaust manifold 11, and a carburetor 12 connected to the intake manifold. As shown, the engine is of the water cooled type having a water conduit 13 leading from its head for connection with a radiator (not shown).

50 Connected to the float chamber 14 of the carburetor 12 is a valve 15, and connected to said valve are gasoline and fuel oil supply pipes 16 and 17, respectively, which are understood to lead from any suitable sources of gasoline and fuel oil supply. The valve 15 is not illustrated in detail as it may be of any suitable or known type operable to selectively place either of the pipes 16 or 17 in communication with the float chamber 14 and to simultaneously deny communication between the other of said pipes and the float chamber. As shown, a handle 18 is connected to the valve 15 and extends therefrom to any suitable point for manipulation by the operator of the

engine to actuate the valve to place either of the pipes 16 or 17 in communication with the carburetor, said handle in the present instance being rotatable through a suitable angle for this purpose.

When the engine is in operation the cooling water contained in the water jacket surrounding the engine cylinder or cylinders, of course, becomes heated, and in accordance with the invention the heated engine cooling water is utilized to heat the fuel oil prior to its introduction into the carburetor 12. To this end a small tank 19 is suitably mounted on or adjacent to the engine and at its bottom and top is connected, as at 20 and 21, respectively, with the top portion of the water jacket of the engine and the conduit 13. Thus, when the water within the water jacket of the engine becomes heated there results a constant circulation of hot water through the tank 19. Moreover, since the tank 19 is connected with the top portion of the water jacket of the engine where the water becomes most quickly heated and where the hottest water tends to accumulate, only a minimum amount of time elapses after starting of the engine until the water circulating through the tank 19 becomes sufficiently hot properly to heat the fuel oil.

Now, in order that the hot water circulating through the tank 19 may be utilized to heat the fuel oil, there is disposed within said tank a coil or coils through which the fuel oil flows in its travel from the tank or other source of supply to the carburetor. Preferably two coils 22 and 23 are employed arranged one within the other with their respective convolutions spaced apart and with the convolutions of each aligned with the spaces between the convolutions of the other, whereby an exceptionally rapid and efficient heating of the oil by the water is obtained. Preferably, too, the coils 22, 23 are formed as a unit separate from the oil supply pipe 17 and the two portions of said pipe are suitably detachably connected with the terminals of said coils. However, the coils may be formed directly in the pipe 17, and, of course, instead of the specific coil arrangement shown and described, any other suitable coil arrangement or heating means for the fuel oil may be provided. An arrangement utilizing the engine cooling water to heat the fuel oil is preferred, however, because of the substantially uniform heat which is derived from this source.

The carburetor 12 includes, as usual, an air supply conduit designated as 24, and in accordance with the invention there is connected with said conduit a hot air supply pipe 25 which leads from a stove or jacket 26 which is suitably mounted in surrounding relationship to the engine exhaust pipe 21. The pipe 25 is connected to the conduit 24 through the instrumentality of a T-fitting or the like 28 the outer end of which is equipped with a hinged closure 29. When this closure is opened atmospheric air may directly and unimpededly enter the air supply conduit 24 of the carburetor without being required to pass through the stove or jacket 26 and the pipe 25. On the other hand, when the closure 29 is closed, all air entering the conduit 24 is required first to pass through the stove or jacket 26 and the pipe 25.

70 The closure 29 is intended to be opened to permit a free flow of atmospheric air to the carburetor when the engine is operating using gasoline as fuel, and to be closed to assure that heated air shall be supplied to the carburetor when the engine is operating using relatively heavy

oil as fuel, air passing through the stove or jacket 26 being heated by the hot exhaust pipe 21 as is, of course, understood.

The reason for opening the closure 29 to admit atmospheric air directly to the carburetor when the engine is operating using gasoline as fuel, and for closing said closure when the engine is operating using relatively heavy oil as fuel, is to render a single adjustment of the fuel control valve of the carburetor suitable for operation of the engine on either gasoline or relatively heavy oil, and to avoid any necessity of changing said adjustment when changing from one fuel to the other. In this connection it has been found that by heating the air supplied to the carburetor when relatively heavy oil is used as fuel the required adjustment of the fuel control valve of the carburetor to obtain most efficient operation of the engine is substantially the same as the adjustment of said valve which is required to obtain most efficient operation of the engine when gasoline is used as fuel and atmospheric air is supplied directly to the carburetor, assuming, of course, that the fuel is in a heated state when it enters the carburetor as is the case according to the invention.

Now, in view of the foregoing, a feature of the invention resides in the provision of means whereby actuation of the handle 18 to cut off communication between the fuel oil supply pipe 17 and the carburetor and to place the gasoline supply pipe 16 in communication with the carburetor, results in opening of the closure 29, and whereby actuation of said handle to cut off communication between the gasoline supply pipe 16 and the carburetor and to place the fuel oil supply pipe 17 in communication with the carburetor, results in closing of the closure 29. The means mentioned may take a variety of forms depending upon the particular installation of the parts constituting the invention, but, as shown, a practical means for the purpose stated may comprise a lever arm 30 fixed to the handle 18 and connected to the closure 29 by a link or rod 31. In addition, a spring 32 preferably is provided to maintain the closure 29 normally closed and to act through the link 31, the lever arm 30 and the handle 18 to maintain the valve 15 normally adjusted to provide communication between the fuel oil supply pipe 17 and the carburetor.

It is desirable to provide means to heat the float chamber 14 of the carburetor, or at least to prevent flow of cooling air thereagainst, to avoid cooling of the fuel oil after it is supplied to the float chamber. Accordingly a trough like shield 33 is provided for this purpose, and, as shown, said shield preferably is mounted to extend between the exhaust manifold 11 and the float chamber 14 so as to direct hot air from the former to the latter.

In view of the foregoing the operation of the present fuel system will be apparent. Assuming that the engine is cold, the handle 18 is actuated to place the gasoline supply pipe 16 in communication with the carburetor and to open the closure 29. The engine then is started in the usual way and as long as the handle 18 is not disturbed the engine operates in the usual way using gasoline as fuel. However, because of the relative cheapness and greater power of fuel oil as fuel, it is desirable to switch over to the use of this fuel as soon as practicable after the engine has been started. Accordingly, following operation of the engine using gasoline as fuel and over a suitable period of time sufficient to heat the

water in the engine jacket and the tank 19, thus to heat the fuel oil, and by which time the exhaust manifold 11 and pipe 21 are hot, the handle 18 is actuated to operate the valve 15 to cut off the supply of gasoline, to place the fuel oil supply pipe 17 in communication with the carburetor and to close the closure 29. Heated fuel oil from the coils 22, 23 and heated air from the stove or jacket 26 then are supplied to the carburetor and the engine continues to operate at high efficiency using the fuel oil as fuel and without requiring any adjustment of the carburetor fuel control valve.

From the foregoing description considered in connection with the accompanying drawing, it is believed that the construction, operation and advantages of the invention will be clearly understood. It is pointed out, however, that while only a single specific structural embodiment of the invention has been illustrated and described, the same is readily susceptible of embodiment in specifically different mechanical structures within its spirit and scope as defined in the appended claims.

25 I claim:

1. In combination with an internal combustion engine including a carburetor, light and heavy fuel supply pipes connected to the carburetor, valve means operable to selectively place said pipes in communication with the carburetor, means for heating the heavy fuel prior to its delivery into the nozzle of the carburetor, an air heating device connected to the air intake conduit of the carburetor, means operable between two positions in one of which it requires air supplied to the carburetor to be first heated by said air heating device and in the other of which it permits atmospheric air to be supplied directly to the carburetor without being heated by said heating device, and means whereby said last mentioned means is operated to its first and second mentioned positions in harmony with actuation of said valve to place the heavy and light fuel supply pipes in communication with the carburetor, respectively.

45 2. In combination with an internal combustion engine including a carburetor, light and heavy fuel supply pipes connected to the carburetor, valve means operable to selectively place said pipes in communication with the carburetor, an air heating device connected to the air intake conduit of the carburetor, a member operable between two positions in one of which it permits atmospheric air to directly enter the air intake conduit of the carburetor and in the other of which it requires air supplied to the carburetor to be first heated by said air heating device, and a connection between said valve means and said member whereby actuation of the valve means to place the light fuel supply pipe in communication with the carburetor actuates said member to its first mentioned position, and whereby actuation of said valve means to place the heavy fuel supply pipe in communication with the carburetor actuates said member to its second mentioned position.

60 3. In combination with an internal combustion engine including a carburetor, light and heavy fuel supply pipes connected to the carburetor, valve means operable to selectively place said

70 pipes in communication with the carburetor, an air heating device connected to the carburetor, a handle for actuating said valve, a member movable between two positions in one of which it permits atmospheric air to be supplied to the carburetor without first being heated by said heating device and in the other of which it requires air supplied to the carburetor to be first heated by said heating device, a valve actuator, and a link and lever connection between said actuator and said member whereby actuation of said actuator to operate the valve means to place the light fuel supply pipe in communication with the carburetor moves said member to its first-mentioned position, and whereby actuation of said actuator to operate the valve means to place the heavy fuel supply pipe in communication with the carburetor moves said member to its second mentioned position.

75 4. In combination with an internal combustion engine including a carburetor, a water jacket and an exhaust conduit, light and heavy fuel supply pipes connected to the carburetor, a valve operable to selectively place said pipes in communication with the carburetor, a handle for actuating said valve, means connected with the water jacket of the engine and utilizing the engine cooling water to heat the heavy fuel prior to its delivery to the carburetor, a jacket cooperating with the exhaust conduit to provide a source of heated air, a connection between said last mentioned jacket and the carburetor, said connection having an opening for the admission of atmospheric air directly to the carburetor, a hinged member for controlling said opening, and a link and lever connection between said valve actuating handle and said member whereby actuation of said handle to place the light fuel supply pipe in communication with the carburetor swings said member to an open position, and whereby actuation of said handle to place the heavy fuel supply pipe in communication with the carburetor results in closing of said member thereby to require air supplied to the carburetor to pass through said jacket.

80 5. In combination with an internal combustion engine including a carburetor, light and heavy fuel supply pipes connected to the carburetor, a valve operable to selectively place said pipes in communication with the carburetor, air heating means connected with the carburetor, said air heating means having an opening for the direct supply of atmospheric air to the carburetor, a member movable to an open position to permit a direct flow of atmospheric air to the carburetor and to a closed position to require air supplied to the carburetor to be first heated by said air heating means, a connection between said member and said valve whereby actuation of the latter to place the light fuel supply pipe in communication with the carburetor moves said member to an open position, and spring means tending constantly to move said member to a position closing said opening and acting through the connection between said member and said valve to maintain the latter normally in a position placing the heavy fuel supply pipe in communication with the carburetor.
